DESIGN FOR AN AUTOMOBILE BODY

Arthur H. Kibiger, Fort Wayne, Ind.

Application July 24, 1933, Serial No. 48,806

Term of patent 3½ years

To all whom it may concern:

Be it known that I, ARTHUR H. KIBIGER, a citizen of the United States, residing at Fort Wayne, in the county of Allen, and State of Indiana, have invented a new, original, and ornamental Design for Automobile Bodies, of which the following is a specification, reference being had to the accompanying drawing forming part thereof.

Figure 1 is a perspective view of an automobile body; Fig. 2 is a front elevation and Fig. 3 is a rear elevation of the same showing my new design.

I claim:

The ornamental design for an automobile body, as shown.

ARTHUR H. KIBIGER.
